UNITED STATES PATENT OFFICE.

WOOD C. DOLLENS, OF DALLAS, TEXAS, ASSIGNOR OF ONE-HALF TO L. M. MARTIN, OF SAME PLACE.

KITCHEN-CABINET.

SPECIFICATION forming part of Letters Patent No. 363,372, dated May 24, 1867.

Application filed October 14, 1866. Serial No. 216,261. (No model.)

To all whom it may concern:

Be it known that I, WOOD C. DOLLENS, a citizen of the United States, residing at Dallas, in the county of Dallas and State of Texas, have invented certain new and useful Improvements in Kitchen-Cabinets; and I do hereby declare the following to be a full, clear, and exact description of the invention, reference being had to the accompanying drawings, and to the letters and figures of reference marked thereon, forming a part of this specification.

My invention relates to improvements in kitchen-cabinets, and is designed to produce a piece of kitchen-furniture which shall combine in a neat, compact, and substantial form various appliances used for culinary purposes, and which shall provide suitable receptacles for the different utensils and materials used in cooking.

To this end my invention consists in the peculiar construction and combination of parts, hereinafter more fully described, and pointed out in the claims.

In the drawings, Figure 1 is a perspective view showing the cutting-board in operative position, and Fig. 2 is perspective view showing the door lowered.

Referring to the drawings, A represents the case or frame of the cabinet, to be attached to the wall of a house at any desired height by hinges *a a*. In the top of this case are the drawers *ff* and compartments *g g g' g'* to receive various articles, the drawers being suitably partitioned to permit different kinds of spices, extracts, &c., to be kept in one drawer without danger of their being intermingled. Directly over the compartments *g g* is a space, *h*, which can be used for the storage of glass-ware, china, &c. This space is closed by door *i*.

F is a compartment in the bottom of the cabinet, somewhat larger than the others, and is designed to be used as a repository for flour, meal, lard, and similar articles.

E is a pie or tart board hinged at *m m* and folding up over the compartments and drawers above. It is provided with an opening, *e*, in which may be inserted the bottom of a pie or other pan, affording a convenient support for it while being filled.

B indicates a door hinged at the front and bottom of the cabinet and folding up against it, where it can be secured by hooks *n n*, or other fastenings. The door *B*, when it is let down to a horizontal position, serves as a 55 kneading or pastry board, and rests upon chopping-board *D*, being supported by the bail *G*.

C represents a cutting-board hinged to the ledge *b* of the door *B*, having inserted therein 60 a knife or slicer, *c*, furnishing an easy and efficient means for slicing apples, potatoes, cabbage, and all other kinds of fruit and vegetables, the sliced portion passing out through the slot *c'*.

D represents a chopping-board hinged to and near the bottom of the door or pastry-board, both the chopping and cutting board being capable of folding back upon the door *D*, where they can be retained in position by hooks 65 *o o' o'*. Upon the under side of the chopping-board is a cushion, *d*, of rubber or other suitable material, to prevent all noise or shocks that might be caused in the chopping or pounding of meat upon the board *D*.

G represents a bail pivotally attached to the sides of case *A*, which can be swung up over the top of the cabinet out of the way when not in use. The cutting-board *C* has notches *k k* in the side pieces, *c' c'*, in which 70 the bail will rest when the board is down and in position for use. When the chopping-board is desired to be used, the hooks *o o* are released and the board lowered until it rests upon the cutting-board *C*. The door or 75 pastry-board *B* can also be let down when desired, in which case it will rest upon the chopping-board *D*, the bail *G* serving as a support for the door and its attachments *C* and *D*.

It will readily be seen from the foregoing 80 description that I furnish a device that will be of inestimable value to housekeepers, combining, as it does, all of the articles used in the performance of their work and occupying but little space.

Having thus described my invention, what 85 I claim as new, and desire to secure by Letters Patent, is—

1. The combination, with a hinged door or lid, of the herein-described separate bail 90

pivotedly secured at its upper ends to the cabinet, and adapted to support on its middle portion the free end of the said door when the latter is in its horizontal position, as set forth.

5 2. In a kitchen-cabinet having a suitable frame, the drawers *f f*, having compartments *g g g' g'* on either side thereof, in combination with the hinged pie-board *E*, having the opening *e*, for the purpose set forth, and which

when raised closes said compartments, substantially as described.

In testimony whereof I affix my signature in presence of two witnesses.

WOOD C. DOLLENS.
